UNITED STATES PATENT OFFICE.

WALTER O. HALL, OF FRANKLIN, MASSACHUSETTS, ASSIGNOR, BY DIRECT AND MESNE ASSIGNMENTS, TO AMERICAN TYPE FOUNDERS COMPANY, OF JERSEY CITY, NEW JERSEY, A CORPORATION OF NEW JERSEY.

DELIVERY MECHANISM.

Original application filed February 26, 1923, Serial No. 621,438. Divided and this application filed June 12, 1924. Serial No. 719,673.

This application is a division of my co-pending application Serial No. 621,438, filed February 26, 1923, for improvements in transfer mechanisms for printing presses.

5 The present invention relates to sheet transfer mechanism for printing presses of the oscillating type, more commonly called "job presses", and is particularly adapted for use with presses of this type which have 10 an oscillating platen and a stationary bed, such as the Golding press.

The problem of producing a practical and efficient automatic sheet feed and delivery for printing presses of the oscillating-platen 15 crank driven type, is of great complexity and difficulty as compared with the problem of producing an automatic device of this kind for presses of the stationary-platen-oscillating-bed type and presses with oscillating platen and bed. Several practical automatic feed and delivery devices have been produced for presses of the latter types, but so far as I am aware no practical mechanism has heretofore been produced for 20 presses of the stationary-bed crank-driven and oscillating-platen-type. The difficulty is due to the movements of the platen on which the sheets are to be deposited and from which the printed sheets are to be 25 taken, and the consequent necessity of so timing the movements of the feeding devices and the delivery devices relative to each other and relative to the oscillation of the platen that they will deposit the sheets 30 on the platen and take the printed sheets therefrom smoothly and without interference with each other or with the platen.

The object of the present invention is to 40 overcome the difficulty referred to above and produce a practical and efficient sheet feed and delivery for presses of the oscillating-platen crank-driven type; and to this end the invention resides in mechanism which will hereinafter be particularly described 45 and the novel features whereof will be pointed out in the claims.

Although the present invention has been 50 designed with particular references to presses of the oscillating-platen crank-driven type, there are certain features of the invention that are applicable to presses of other types, as will be apparent hereinafter.

Generally stated, the sheet feeding and delivery mechanism of the present invention comprises two or more pairs of horizontally aligned sheet feeding fingers mounted to oscillate bodily in vertical planes intersecting the platen and moving in paths extending from elevated points in front of the press to points adjacent the lower edge 55 of the platen, and a similar set of delivery fingers mounted to oscillate in a path, below the path of the feeding fingers, extending from points in front of the press to points on the face of the platen adjacent the tail edge of the sheet thereon; combined with automatic means for closing the feeding fingers on a sheet, presented thereto by a suitable sheet feeding device, and for opening 60 said fingers when they approach the limit of their movement towards the platen, to deposit the sheet thereon; and automatic devices for closing the delivery fingers on the tail edge of a sheet carried by the platen, and opening 65 said fingers to release the sheet 70 when the fingers approach the opposite limit on their movement. The means for oscillating the feeding fingers preferably includes crank and lever mechanism operating to slow down the movement of said 75 fingers as they approach and recede from the terminal points, so as to allow sufficient time for the platen to open and clear said fingers as they cross the edge of the platen, and so as to permit the delivery fingers to abstract 80 the printed sheet from the platen before the feeding fingers deposit the blank thereon. The means for oscillating the delivery fingers also comprises crank and lever 85 mechanism and preferably said mechanism 90 includes two separate gear trains from the operating shaft of the press so designed as to impart to said fingers a resultant movement which is accelerated while said fingers are moving to and fro over the platen, to 95 cause said fingers to move quickly across the platen, grasp the sheet thereon, and move quickly back out of the way of the feeding fingers, which are simultaneously moving over the platen but with a relatively low velocity. 100 In this manner the feeding and delivery devices are projected and retracted across the face of the platen in such timed relation to the oscillation thereof and with such rela-

tive velocities that the sheets are deposited thereon and abstracted therefrom smoothly and without interference.

Referring to the accompanying drawings 5 for a particular description of mechanism embodying the present invention:

Fig. 1 is a side view of sheet feeding and delivery mechanism constructed in accordance with the invention and applied to a 10 Golding press;

Fig. 2 is a front elevation, looking towards the right of Fig. 1;

Fig. 3 is a plan view looking down on Fig. 15 1 of the sheet feeding and delivery carriages and their associated operating mechanism;

Fig. 4 is a sectional plan view taken on line 4-4 of Fig. 1;

Fig. 5 is a detail side view of the means 20 for mounting and operating the sheet gripping fingers;

Fig. 6 is a detail view illustrating the position of parts when the delivery gripper fingers are in open position;

Fig. 7 is a detail view of a shaft on which 25 the upper gripper fingers are adapted to be mounted;

Fig. 8 is a plan view of a carriage for the 30 delivery mechanism showing a modification of means for adjusting the throw of said carriage;

Fig. 9 is a detail view of a driving means for the delivery carriage;

Fig. 10 is a detail view illustrating the adjustable mounting of the sheet gripping fingers; and 35

Fig. 11 is a detail view showing clamping devices between the auxiliary frame and frame of the press.

Referring to the drawings, Fig. 1 shows 40 only sufficient parts of a press of the Golding type to illustrate the application of the present invention thereto. A designates the frame; B, the stationary form bed; and C, the oscillating platen. The platen, pivoted to the frame at D, is operated by well known mechanism shown partly in dotted lines in Fig. 1. Said mechanism is operated from a power or driving shaft 1 carrying a pinion 2 which meshes with a large gear 3 on a 45 main operating shaft 4; and comprises a crank 5 on shaft 4, a link 6 connecting said crank to radius bars 7; a toggle 8, 9 connecting the radius bars to the platen, and a pair of draw bars 10 connecting the toggle with frame A and extending across the ends 50 of the platen.

The sheet feeding and delivery mechanism is adapted to be mounted on an auxiliary frame attached to the press frame A and extending across and spaced from the front of the press. This auxiliary frame is shown in side elevation in Fig. 1 and in front elevation in Fig. 2. It is of rectangular form and comprises vertical side bars 11 connected at 60 their upper ends by a horizontal bar 12 and

braced at their lower ends by a rod 13. Said auxiliary frame is preferably pivotally mounted at the side on the press frame, so that it may be swung horizontally, with the sheet feeding and delivery mechanism carried thereby, ninety degrees or more from operative position, to permit access to the press. For this purpose one of the side bars 11 has a pair of parallel arms 14 extending 70 towards the press and terminating in bifurcations 14^a which are adapted to straddle lugs 15^a formed on the ends of a pair of brackets 15 secured to and projecting from the sides of frame A. The bifurcated ends of arms 14 have vertical perforations which 75 register with perforations in the lugs of brackets 15, and pins 14^b passing through these perforations pivotally connect the frames. The other side bar 11 has a pair of parallel arms 14 which extend towards the frame 15 and terminate in right angular portions 14^c which have open slots to receive threaded bolts 14^d hinged to the frame. Bolts 14^d are provided with knurled pieces 80 14^e. When the pieces 14^e are unscrewed and bolts 14^d swung out of the slots in 14^c and the operating links between the driving shaft of the press and the sheet conveying mechanism are disconnected, the auxiliary frame and said mechanism may be swung 85 about a vertical axis to the side entirely out of the way of the bed and platen.

The mechanism for feeding sheets to the platen comprises two or more pairs of sheet gripping fingers supported from a pair of arms 16, which are keyed to the ends of a horizontal shaft 17 journaled in the side bars 11. The arms 16 are oscillated by mechanism comprising a link 18 connected at one end to one of said arms and at its other to a crank 19 secured to the large gear wheel 3. Each pair of sheet gripping fingers, as more clearly shown in Figures 5, 6 and 10, consists of an upper movable finger 20 and a lower relatively stationary finger 21. The upper fingers 20 are secured to split collars 20^a which are adjustably mounted on a shaft 22, which extends transversely between the arms 16 and is rotatably supported in the ends of said arms. The lower relatively stationary fingers 21 are attached to dove-tail blocks 21^a which are frictionally held in a dove-tail groove formed on the underside of a rod 23, which acts both as a support for said fingers and a tie rod for arms 16. The fingers are thus adjustable longitudinally of the shaft and rod to suit sheets of different widths.

Secured to shaft 22 outside of the arm 16 is an arm 24 carrying a roller 25 at its free end. Inside of the arm 16 the shaft 22 carries a collar 26 in which is formed a notch 27. A spring 28, secured at one end to arm 16 and at its other end to shaft 22, tends to rotate said shaft in a direction to close the 125 130

5 fingers 20 on the relatively stationary fingers 21. The fingers 20 are moved to open position, or cocked, by roller 25 coming in contact with draw bar 10, as the feeding mechanism approaches the limit of its movement towards the platen. Said fingers are held open during the return movement of the feeding mechanism, and until the latter approaches the limits of its movement toward 10 a pile of sheets, by means of a pawl 29 engaging the notch 27 in collar 26. Pawl 29 is attached to or integrally formed with an arm 30, which is pivoted on the tie rod 23 inside of the arm 16 and urged by a suitable spring 15 in a direction to engage said pawl with the notch. An arm 30 carries a roller 31 which engages a cam 32 when the sheet feeding mechanism approaches the limit of its movement towards the sheet pile. As said roller 20 travels along the cam, arm 30 is rotated in a direction to raise the pawl out of the notch, permitting spring 28 to rotate shaft 22 and close, or uncock, fingers 20. As said fingers close, they grip a sheet against the relatively 25 stationary fingers 21, said sheet having been presented to grippers 20 and 21 by any suitable automatic sheet feeding device.

The mechanism for taking the printed sheets from the platen and delivering same 30 to a suitable conveyor comprises sheet gripping fingers supported by a carriage 33 which reciprocates on a fixed track 34 rigidly attached at one end to a side of the auxiliary frame. Like the said grippers, the delivery grippers consist of two or more pairs 35 of fingers, the members of which are mounted respectively on a shaft and a rod extending transversely between the sides of the carriage. Each pair of these fingers consists 40 of a relatively stationary lower finger 35 adjustably secured to the underside of a tie rod 36, and an upper movable finger 37 adjustably mounted on the upper side of a shaft 37^a. The fingers are adjustable longitudinally of the shaft and rod to conform 45 with differences in sheet widths.

An arm 38 on shaft 37^a has a notched boss, formed with a notch 38^a which is adapted to be engaged by a pawl 39 secured to an arm 50 39 which is pivoted on tie rod 36; and the shaft 37^a is urged by a suitable spring 37^b in a direction to close fingers 37 on the relatively stationary fingers 35, the construction being similar to the construction of the controlling means for the feed fingers above described.

When carriage 33 approaches the limit of its movement away from the platen, a roller 38^b on arm 38 contacts a cam 40 (Fig. 2), 55 which is adjustably mounted on a bracket 40^a projecting inwardly from a side bar 11. This causes rotation of shaft 37^a and consequent opening, or cocking, of fingers 39, and causes release of the sheet. Fingers 39 are 60 held open, or cocked, during the return

movement of the carriage, and until the latter approaches the limit of its movement towards the platen, by the pawl 39^a on arm 39 engaging the notch in the boss of arm 38. As the carriage approaches the limit of its movement towards the platen the tail edge 70 of the sheet thereon enters between the gripping fingers and the roller 39^b on arm 39 contacts a projection on the platen, thus moving the pawl out of the notch 38^a and permitting shaft 37^a to uncock fingers 39, and rotate them in sheet clamping relation to the relatively stationary fingers 35.

The carriage 33 is operated by mechanism now to be described. Journaled on shaft 17, inside the arms 16, are a pair of spaced toothed segments 41 which are rigidly connected together by a bar 42. One of the segments 41 is connected to one end of a link 43, the other end of which is bifurcated to straddle shaft 4. A cap 44 attached to the ends of the bifurcated portions of link 43 carries a collar 45 which operates in a cam track 46 formed on the inner face of a disc 47 keyed on shaft 4. A sleeve 48 on shaft 17 extends completely between the segment 41 and formed integrally with said sleeve are two arms 49 which extend upwardly adjacent the segments 41 and have pivoted at their upper ends a pair of toothed segments 50 which mesh with the segments 41. Secured to segments 50 are upwardly extending arms 51 on the free ends of which are pivoted swivel blocks 52.

Blocks 52 are bored through to receive tubular extensions on carriage 33, being adjustably secured to the blocks by set screws 53. Formed integrally with sleeve 48 at one end thereof, is a depending arm 54 which is pivoted to one end of a link 55, the other end of said link being connected to a crank 56 on the shaft 4.

In Fig. 1 the platen is shown in open position with the sheet feeding devices moving thereover towards their sheet depositing position with a sheet S, while the sheet delivery devices are at the limit of their movement towards the platen with the gripping fingers thereof closed on the tail edge of a printed sheet. The shaft 4 is moving counter-clockwise and the crank 19 is pulling the link 18 and moving the arms 16 downwardly, while the crank 56 and the cam 46 are on the point of moving link 55 to the right of the link 43 to the left, as viewed in Fig. 1. As shaft 4 continues to rotate from the position shown in Fig. 1, the cam track 46 will move the link 43 to the left with a relatively quick movement while the crank 56 will operate to move link 55 to the right. Hence segments 41 will rotate in a clockwise direction while arms 49 will rotate in a counter-clockwise direction. Segments 50 and the arms 51 rigid therewith will thus be rotated counter-clockwise bodily about the 110 115 120 125 130

- axis of shaft 17 and also in the same direction about their pivotal connections with arms 49, the bodily movement of said segments being derived from the rotation of arms 49 by the link 55 and crank 56 and the pivotal movements of said segments on said arms 49 being derived from the rotation of segment 41 and also from the bodily movement of segment 50 on segment 41.
- 10 Hence the arms 51 have a resultant movement which is produced by the two separate cam and crank connections, and as will be obvious by an inspection of the construction and relative position of the parts shown by
- 15 Fig. 1, the motion of arms 51 is greatly accelerated during the movements of the delivery fingers over the platen face. Hence the delivery fingers will move down quickly over the platen to the position shown in Fig.
- 20 1 seize the sheet thereon, and move same with equal quickness out of the way of the sheet which the feed fingers are on the point of depositing.
- 25 While the delivery fingers are thus moving over the platen to seize the printed sheet and take same to a suitable point of delivery, the crank 19 is moving the arms 16 with the feed fingers carried thereby from points adjacent the pile P of sheets, down over the
- 30 platen to their sheet depositing position. When arms 16 approach the limit of their downward movement, the roller 25 on arm 24 makes contact with draw bar 10, thus rotating fingers 20 and releasing the sheet,
- 35 which falls on the platen, the progress of said sheet being stopped by register fingers 57 which are adjustably attached in any known manner to the lower edge of said platen. The feed fingers have a slightly
- 40 further downward movement after depositing the sheet which permits them to clear the head of the sheet on their return movement, said fingers during this further movement operating to hold said sheet down on the platen.
- 45 As the delivery mechanism approaches the limit of its movement away from the platen the roller 38^b on arm 38 makes contact with the cam 40, rotating fingers 37 and releasing the sheet held thereby. Any suitable conveying means may be employed for receiving the sheets from the delivery fingers and conveying same to a desired point. Fingers 37 are held in open position by the pawl 39^a on
- 50 arm 39 engaging the notch 38^a in the boss of arm 38 and are held open until the roller 39^b on arm 39 makes contact with a projection on the platen outside of the sheet after the fingers have received between them the tail
- 55 edge of the printed sheet. It will be observed that the delivery mechanism has a substantial dwell at the limit of its movement away from the platen, due to the fact that the cam track 46 is substantially concentric with shaft 4 and the crank 56 is pass-

ing over its dead center while the mechanism occupies this position. This gives ample time for the sheet to fall from sheet delivery fingers and makes it possible to produce the quick movements of said fingers over the 70 platen. It will also be observed that due to the relative positions of the axes of shafts 17 and 4, the crank 19 will give a relatively slow movement to the arms 16 and the feed mechanism carried thereby while said mechanism is approaching the platen and a fast movement away from the platen. Hence ample time will be allowed for the platen to open and clear the feeding fingers as they cross the edge thereof and for the delivery 80 fingers to withdraw the printed sheet from the platen before the feeding mechanism deposits a sheet thereon.

As the sheets operated on vary in width, it is necessary to adjust for these variations. 85 Therefore the feeding fingers are mounted so that they may be clamped or secured at different points on the shafts 22 and rod 23, while the delivery fingers are adjustable in a similar manner on the shaft 37^a and rod 36, 90 as shown in Figure 10, and the register fingers 57 are attachable at different points along the edge of the platen. By these means the mechanism is adjustable for any width sheet within the platen range. For 95 adjusting to suit different lengths of sheets the carriage 33 is moved relatively to the swivel blocks 52 and clamped by the set screws 53 or other suitable clamping means in proper position for the particular length 100 of sheet operated on.

Figure 8 illustrates a modification of the means for adjusting the carriage relatively to the swivel blocks. In this modification the bores of the swivel blocks are threaded 105 to receive threaded shafts 58, which are rotatably mounted in a cross piece 59 of the carriage. A shaft 60 journaled in the sides of the carriage has bevel gear connections with the ends of sheets 58, and said shaft 60 110 has a square end 61 which is adapted for engagement by a suitable tool, whereby said shafts may be rotated and the carriage moved closer to or further from the swivel blocks 52, according as the sheets are longer 115 or shorter.

Although an embodiment of the invention has been described in detail, it is not limited to the form shown but includes modifications and changes with the scope of the appended 120 claims.

Having thus described my invention what I claim as new and desire to secure by Letters Patent is:

1. Automatic sheet delivery mechanism 125 for printing presses of the oscillating type, including in combination, sheet gripping fingers mounted for reciprocation in a curved path extending from the face of the platen adjacent the tail edge of the sheet operated 130

- on to points outside the press, means for reciprocating said fingers in timed relation to the oscillation of said press, including a swinging member having a pivot below the path of the sheets, said means being adjustable whereby the termination of the path of the gripping fingers on the platen face may be varied in accordance with the length of the sheets, means for opening said fingers 5
- 10 when they approach the limit of their movement away from the platen, means for holding said fingers open during the movement toward the platen, and means for releasing said holding means to permit said fingers to close on a sheet when said fingers approach the limit of their movement towards the platen.
2. In combination with a printing press of the oscillating type, sheet delivery mechanism comprising a plurality of pairs of horizontally aligned sheet gripping fingers mounted to reciprocate in parallel vertical planes intersecting the platen, means operated in timed relation to the oscillation 20 of the press for reciprocating said fingers in curved paths extending from points substantially on the platen face well below the upper edge of the platen to points outside the press, including a swinging arm having a pivot 25 spaced from the concave side of said path, and automatic means for actuating said gripping fingers as they approach the limits of their movement, to cause said fingers to take a sheet from the platen and release same at a point outside the press.
3. In combination with a printing press of the oscillating type, sheet delivery mechanism comprising a carriage, a track guiding said carriage to and from the platen, means for reciprocating said carriage in timed relation to the oscillation of the press, said means operating to impart to said carriage an accelerated motion over the platen and a substantial dwell at the limit of its 40 movement away from the platen, sheet gripping devices mounted on said carriage, and means for actuating said gripping devices to cause them to take a sheet from the platen and release same at points outside the press.
4. Automatic sheet delivery mechanism for printing presses of the oscillating platen type, comprising sheet gripping fingers mounted to reciprocate in a curved path extending from points substantially on the 45 face of the platen well below the upper edge thereof, when the latter is open, to points in front of the press, means for reciprocating said fingers in timed relation to the oscillation of said platen including a swinging arm approximately normal to said path throughout its movement, means for opening said fingers to release the sheet carried thereby when said fingers approach the limit of their movement away from the platen, means for 50 holding said fingers open, and means for releasing said holding means to permit said fingers to close on a sheet carried by the platen when said fingers approach the limit of their movement towards said platen.
5. Automatic sheet delivery mechanism 55 for printing presses of the oscillating platen type, comprising sheet gripping fingers mounted to reciprocate bodily in a curved path extending from points substantially on the platen face and sharply inclined to the plane of said face, when the platen is fully open, to elevated points in front of the press, means for adjusting the limit of the movement of said fingers towards said platen, means for reciprocating said fingers in timed relation to the oscillation of said platen, means for opening said fingers when they approach the limit of their movement away from the platen, means for holding said fingers open, and means for releasing said holding means to permit said fingers to close when they approach the limit of their movement towards said platen.
6. In combination with a printing press of the oscillating platen type, sheet delivery mechanism comprising a plurality of pairs of horizontally aligned sheet gripping fingers mounted to reciprocate in parallel paths intersecting the platen at an angle sharply inclined to the plane of the platen and located well below the upper edge of said platen, means operated in timed relation to the oscillation of said platen for reciprocating said fingers in said paths, and automatic means for actuating said gripping fingers as they approach the limits of their movements to cause said fingers to take a sheet from the platen and release same at a point in front of the press.
7. In combination with a printing press of the oscillating platen type, sheet delivery mechanism comprising a plurality of pairs of horizontally aligned sheet gripping fingers mounted to reciprocate in parallel vertical planes intersecting the platen, means operated in timed relation to the oscillation of said platen for reciprocating said fingers in curved paths from points substantially on the platen face, when said platen is fully open, to elevated points in front of the press, the prolongations of said paths intersecting the platen at small acute angles, said means being adjustable to vary the limit of movement of said fingers towards said platen, and automatic means for actuating said gripping fingers as they approach the limits of their movements, to cause said fingers to take a sheet from the platen and release same at an elevated point in front of the press.
8. In combination with a printing press of the oscillating platen type, sheet delivery mechanism comprising a plurality of pairs of sheet gripping fingers mounted to reciprocate in vertical parallel planes intersecting 100
- 105
- 110
- 115
- 120
- 125
- 130

the platen face, means actuated by an operating shaft of the press for reciprocating said fingers from point substantially on the platen, when the latter is open, to elevated points in 5 front of the press, said means operating to accelerate the movement of said fingers over the platen face, and automatic means for closing said gripper fingers when they approach the limit of their movement towards 10 the platen and for opening said fingers when they approach the opposite limit of their movement.

9. In combination with a printing press of the oscillating platen type, sheet delivery 15 mechanism comprising an upwardly extending arm mounted in front of the press, means actuated by an operating shaft of the press for oscillating said arm towards and from the press, a transversely extending carriage 20 having a pivotal connection with the upper end of said arm and adapted to be reciprocated thereby across the face of the platen, said pivotal connection being adjustable to vary the limits of carriage movement, means for guiding said carriage, and 25 sheet gripping devices mounted on said carriage.

10. In combination with a printing press of the oscillating platen type, sheet delivery 30 mechanism comprising a transversely extending carriage, a track guiding said carriage for reciprocation to and from the platen, means for reciprocating said carriage in timed relation to the oscillation of said 35 platen, said means operating to give said carriage an accelerated motion over the face of said platen, sheet gripping devices mounted on said carriage, and means for actuating said gripping devices to cause them 40 to take a sheet from the platen and release same at an elevated point in front of the press.

11. In combination with a printing press of the oscillating platen type, sheet delivery 45 mechanism comprising an upwardly extending arm mounted in front of the press, sheet gripping devices connected to said arm and adapted to be reciprocated thereby across the platen face, connections between said arm 50 and an operating shaft of the press for oscillating said arm in timed relation to the oscillation of said platen, said connections being constructed to give said gripping devices a relatively quick motion as they travel 55 to and fro across the platen face.

12. In combination with a printing press of the oscillating platen type, sheet delivery mechanism comprising an upwardly extending arm mounted in front of the press, sheet 60 gripping devices connected to said arm and adapted to be reciprocated thereby across the platen face, a driving connection between said arm and an operating shaft of the press, a separate driving connection between said 65 arm and said shaft, whereby said arm is

oscillated with a resultant motion derived from said separate connections, said connections being so constructed that said resultant motion is accelerated as said gripping devices move over the face of said platen. 70

13. In combination with a printing press of the oscillating platen type, sheet delivery mechanism comprising a transverse horizontal shaft mounted in front of the press, a pair of rigidly connected spaced toothed segments rotatable on said shaft, a depending arm rigid with one of said segments, a disc on the operating shaft of the press having a cam track on a face thereof, a link connected at one end to said depending arm and having its other end engaging said cam track, a sleeve on said shaft between said segments, upwardly extending arms rigid with said sleeve, toothed segments pivoted on said arms meshing with said first mentioned toothed segments, a depending arm rigid with said second mentioned toothed segments, blocks swivelled in the upper ends of said last mentioned arms, a carriage having extensions passing through said blocks and adjustably fastened thereto, a stationary cam track, a roller on said carriage travelling on said track, a transverse shaft journaled in the sides of said carriage, a tie rod connecting said sides, upper and lower sheet gripping fingers adjustably fixed to said shaft and rod respectively, said shaft being biased to hold said fingers closed, an arm on said shaft, a stationary adjustable cam adapted to contact said arm and open said fingers when said carriage approaches the limit of its movement away from the 90 platen, a detent holding said shaft, an arm connected to said detent, and means to contact said last mentioned arm and release said shaft to permit said fingers to close 95 when said carriage approaches the limit of its movement towards the platen. 100

14. In combination with a printing press of the oscillating platen type, sheet delivery mechanism adapted to take a printed sheet from the platen and release same at an elevated point in front of the press, comprising a transverse horizontal shaft journaled in front of the press, a pair of rigidly connected spaced toothed segments rotatable on said shaft, a depending arm rigid with one of said segments, a disc on the operating shaft of the press having a cam track on a face thereof, a link connected at one end to said depending arm and having a roller at its other end engaging said cam track, a sleeve on said shaft between said segments, upwardly extending arms rigid with said sleeve, toothed segments pivoted on said arms meshing with said first mentioned toothed segments, a depending arm rigid 120 125 130

- with said sleeve, a crank on said press operating shaft, a link connecting said crank to said depending arm, upwardly extending arms rigid with said second mentioned toothed segments, a carriage having extensions pivoted to said arms, a cam track guiding said carriage for movement across the face of said platen, and sheet gripping and releasing devices mounted on said carriage.
15. In combination with a printing press of the oscillating platen type, sheet delivery mechanism adapted to take a printed sheet from the platen and deliver same at an elevated point in front of the press, comprising a pair of toothed segments rotatably mounted on a horizontal axis in front of the press, means actuated by an operating shaft of the press for oscillating said segments, upwardly extending arms rotatably mounted on said axis, toothed segments pivoted on said arms meshing with said first mentioned toothed segments, means actuated by said press operating shaft for oscillating said arms, upwardly extending arms rigid with said second mentioned toothed segments, a carriage having extensions pivoted to said arms, a cam track guiding said carriage for movement across the face of said platen, and sheet gripping and releasing devices mounted on said carriage.
16. In combination with a printing press of the oscillating platen type, sheet delivery mechanism adapted to take a printed sheet from the platen and deliver same at an elevated point in front of the press, comprising a toothed segment rotatably mounted on a horizontal axis in front of the press, a depending arm rigid with said segment, a disc on the operating shaft of the press having a cam track on a face thereof, a link connected at one end to said depending arm and having a roller at its other end engaging said cam track, an upwardly extending arm rotatable on said axis adjacent said segment, a toothed segment pivoted on said arm meshing with said first mentioned toothed segment, a crank on said press operating shaft, a link connecting said crank to said upwardly extending arm, an upwardly extending arm rigid with said second mentioned toothed segment, a block swiveled to the upper end of said last mentioned arm, a carriage having an extension passing through said block and adjustably fastened therein, a stationary cam track supporting and guiding said carriage, a transverse shaft journaled in said carriage, a rod fixed to said carriage and extending parallel to said transverse shaft, upper and lower gripper fingers adjustably mounted on said shaft and rod respectively, said shaft being biased to hold said fingers closed, an arm on said shaft, a stationary adjustable cam adapted to contact said arm and open said fingers when said carriage
- approaches the limit of its movement away from the platen, a detent holding said shaft, an arm connected to said detent, and means to contact said last mentioned arm and release said shaft to permit said fingers to close when said carriage approaches the limit of its movement towards the platen.
17. In combination with a printing press of the oscillating platen type, sheet delivery mechanism adapted to take a printed sheet from the platen and deliver same at an elevated point in front of the press, comprising a gear rotatably mounted on a horizontal axis in front of the press, a cam on the operating shaft of the press, a link connecting said cam to said gear for oscillating said gear, an upwardly extending arm rotatable on said axis adjacent said gear, a gear pivoted on said arm meshing with said first mentioned gear, a crank on said press operating shaft, a link connecting said crank to said arm, an upwardly extending arm rigid with second mentioned gear, and sheet gripping and releasing devices connected for operation by said last mentioned arm.
18. In combination with a printing press of the oscillating platen type, sheet delivery mechanism adapted to take a printed sheet from the platen and deliver same at an elevated point in front of the press, comprising a gear rotatably mounted on a horizontal axis in front of the press, means actuated by an operating shaft of the press for oscillating said gear, an upwardly extending arm rotatable on said axis adjacent said gear, a gear pivoted on said arm meshing with said first mentioned gear, means actuated by an operating shaft of the press for oscillating said arm, an upwardly extending arm rigid with said second mentioned gear, and sheet gripping and releasing devices connected for operation by said last mentioned arm.
19. In combination with a printing press of the oscillating platen type, sheet delivery mechanism adapted to take a printed sheet from the platen and deliver same at an elevated point in front of the press, comprising a transverse horizontal shaft journaled in front of the press, a pair of rigidly connected spaced apart toothed segments rotatable on said shaft, a depending arm rigid with one of said segments, a connection between said depending arm and an operating shaft of the press oscillating said arm and segments, a sleeve on said shaft between said segments, upwardly extending arms rigid with said sleeve, toothed segments pivoted on said arms meshing with said first mentioned toothed segments, a depending arm rigid with said sleeve, a connection between said last mentioned depending arm and said press operating shaft for oscillating said arm, upwardly extending arms rigid with said second mentioned toothed segments, and sheet gripping and releasing de-

vinces connected for operation by said last mentioned arms.

20. In a sheet delivery mechanism for printing presses of the oscillating platen type, a cam track fixed at one end extending towards the platen, a carriage movable on said cam track, sheet gripping and releasing devices mounted on said carriage, an upwardly extending arm mounted in front of the platen, means for oscillating said arm in timed relation to the oscillation of said platen, a block swivelled on a horizontal axis to the upper end of said arm, said block having a threaded bore, a threaded shaft 10
15 rotatably mounted on said carriage and extending through said bore, and means for rotating said shaft to adjust the throw of said carriage.

21. In a sheet delivery mechanism for printing presses of the oscillating platen type, an upwardly extending arm mounted in front of the platen, means for oscillating said arm in timed relation to the oscillation of said platen, a block swivelled to the upper end of said arm on a horizontal axis, 20
25 a carriage mounted for reciprocation over the face of said platen, sheet gripping and releasing devices carried by said carriage, and a connection between said carriage and arm comprising a threaded shaft rotatably mounted on said carriage and screwed through said block.

In testimony whereof I hereunto affix my signature.

WALTER O. HALL.
